UNITED STATES PATENT OFFICE

143,161

DESIGN FOR A REFRIGERATING UNIT

Frederic G. Peck, Upper Darby, Pa., assignor to
Merchant & Evans Company, Philadelphia, Pa.,
a corporation of Pennsylvania

Application May 31, 1945, Serial No. 119,828

Term of patent 7 years

(Cl. D62—4)

To all whom it may concern:

Be it known that I, Frederic G. Peck, a citizen
of the United States, residing in Upper Darby,
Delaware County, Pennsylvania, have invented a
new, original, and ornamental Design for a Re-
frigerating Unit, of which the following is a spec-
ification, reference being had to the accompan-
ying drawing, forming a part thereof.

Fig. 1 is a perspective view of a refrigerating
unit showing my new design;

Fig. 2 is a side elevation thereof; and
Fig. 3 is a rear elevation thereof.

I claim:

The ornamental design for a refrigerating unit,
as shown.

FREDERIC G. PECK.
